UNITED STATES PATENT OFFICE.

THOMAS GREEN BULLARD, OF ENTERPRISE, ALABAMA.

STOP MOTION FOR SPINNING FRAMES.

1,403,386.

Specification of Letters Patent. Patented Jan. 10, 1922.

Application filed August 22, 1919. Serial No. 319,255.

To all whom it may concern:

Be it known that THOMAS G. BULLARD, a citizen of the United States of America, residing at Enterprise, in the county of 5 Coffee and State of Alabama, has invented new and useful Improvements in Stop Motions for Spinning Frames, of which the following is a specification.

The object of the invention is to provide 10 a simple, relatively inexpensive and efficient apparatus suitable for application to spinning frames of the ordinary and well-known constructions for stopping the machine by shifting the drive belt from the fixed to the 15 loose pulley when the operation of winding the yarn upon the bobbins or quills has been completed or when said bobbins or quills have been filled, to avoid the over-filling thereof or the superfluous winding of 20 the same, and thus to avoid the disadvantages of overrun bobbins and the loss incident to waste and tangled yarn resulting therefrom, and to this end the invention consists in a 25 construction and combination of parts of which a preferred embodiment is shown in the accompanying drawings, it being obvious that changes in form and proportion, in adapting the mechanism to spinning frames of different constructions may be resorted to, 30 within the scope of the appended claims without departing from the principles involved.

In the drawing:

Figure 1 is a plan view of the apparatus 35 applied in the operative position to a spinning frame.

Figure 2 is a detail view of the shipper arm.

Figure 3 is a similar view of the auxiliary 40 shipper rod.

Figure 4 is a similar view of the trigger or latch.

Figure 5 is a similar view of the guide for 45 the auxiliary shipper rod.

Figure 6 is a detail elevational view showing the end of the latch bar and its relation to the ring rail and thread rail.

Figure 7 is a sectional view taken on the 50 plane indicated by the line 7-7 of Figure 6.

Those parts of an ordinary spinning frame in connection with which the stop motion contemplated by the invention cooperates and which are therefore essential to an understanding of the invention are the ring or 55 separator blade rails 10, the thread rail 11, the main or ordinary shipper rod 12 with

which is connected the belt shifting arm 13 and the fast and loose belt pulleys 14 and 15.

Suitably mounted for sliding movement in bearings in the frame 16 of the machine is 60 an auxiliary shipper rod 17 extending at an intermediate point through a guide 18 which may be supported as indicated, from the thread rail 11 to which it may be secured by a screw 19, and carried by said auxiliary 65 shipper rod is a shipper arm or follower 20 deflected or slotted as at 21 to engage the main shipper rod and contact with a stop 22 thereon, said stop in the construction illustrated consisting of an element of the main 70 shipper rod, namely a coupling 23 which serves to control the position of the stem 24 of the belt shifter arm with relation to the body portion of the said shipper rod. It is 75 obvious that any other suitable form of stop may be used in this connection as a means whereby motion of the shipper arm or follower 20 may be communicated to the main shipper rod and hence to the belt shifter arm.

The means for impelling the auxiliary shipper rod in the direction to cause the shifting of the belt consists, in the construction illustrated, of a coil spring 25 in surrounding relation to the auxiliary shipper rod 85 and compressed between the arm 20 and the guide 18, so that the action of the spring is to impel the auxiliary shipper rod in a direction away from the trigger or latch bar 26 which is terminally arranged in the path of 90 upward movement of the separator blade or ring rail 10 which normally engages a notch or seat 27 formed in the auxiliary shipper rod. That the trigger bar 26 may readily engage with or be readily disengaged from the 95 notch or seat 27, it must be susceptible of movement in a vertical plane and such movement is imparted to it by the rising ring rail in the operation of laying the yarn on the spindles. For this reason, the thread rails 11 100 which support the latch bar are formed with openings 28 whose width is substantially the width of the latch bar and whose height is sufficient to provide a slight upward or vertical movement of the latch bar, the cotter 105 pins 29 serving to preclude longitudinal movement of the latch bar and thus ensuring it always being in a position for engagement by the ring rail.

When the mechanism is in operation and 110 yarn is being applied to the bobbins, the belt of course traverses the tight pulley 14 to im-

part movement to the machine and the belt shifting arm 13 is then in the position indicated in dotted lines in Figure 1, the auxiliary shipper rod and its attendant parts 5 being also in the position indicated in the dotted lines in said figure. In such a position, the notch 27 is disposed at a point where it is engaged by the latch bar 26, the latter being maintained in contact with the 10 seat by gravity. In such a position of the parts the spring 25 is under compression and when the bobbins have been filled and the separator blade or ring rail rises on the last beat or stroke of laying the yarn on the 15 quills, it engages the projecting extremities of the latch bar, raising the same from engagement with the notch or seat 27, when the spring 25 is free to act and, through the shipper arm 20, imparts longitudinal movement to the stem 24 of the belt shifter, moving the said shifter to the full line position shown in Figure 1 when the belt is perforce transferred to the loose pulley and the mechanism comes to rest.

20

25 It is obvious that an apparatus as described may be readily applied at small cost to any of the ordinary forms of spinning frames, and will serve as a positive means of preventing the overrunning of the bobbins 30 or quills and hence the waste and loss both in the matter of yarn and time incident thereto.

What is claimed is:

1. In a stop motion for spinning frames, 35 the combination of a transversely disposed trigger or latch bar spanning the frame and mounted for slight vertical movement but precluded from longitudinal movement and having its extremities arranged in the path 40 of movement of the ring rails, a belt shifter, and a spring actuated shipper rod operatively engaged with said shifter and provided with a seat or notch for engagement by said latch bar.
- 45 2. In a stop motion for spinning frames, the combination of a transversely disposed

latch or trigger bar spanning the frame and mounted for slight vertical movement but precluded from longitudinal movement and having its extremities arranged in the path 50 of movement of the ring rails, a belt shifter, an auxiliary shipper rod, operative connections between the auxiliary shipper rod and the belt shifter, and a spring operatively connected with the auxiliary shipper rod 55 and tending to force the belt shifter to a position guiding the belt on to the idle or loose pulley of the frame, the auxiliary shipper rod being formed with a notch or seat for engagement by the latch bar to hold the auxiliary rod in a retracted position 60 whereby the belt shifter may be moved to guide the belt on to the tight pulley of the frame, the said latch bar being disengagable from said notch or seat by the ring rails 65 on the upward movement of the latter.

3. In a stop motion for spinning frames, the combination with a transversely disposed latch bar spanning the frame and mounted in holes formed therein and extended in the direction of their length or height to provide for slight upward movement of the latch bar, the latter having means to preclude its longitudinal movement and having its extremities arranged in the path of movement of the ring rails, a belt shifter, an auxiliary shipper rod, a guide in which said auxiliary shipper rod is slidably mounted, a shifter arm carried by said auxiliary shipper rod and operatively engaged with the 70 belt shifter, and a spring compressed between said guide and said arm, the said spring being in surrounding relation to the auxiliary shipper rod and the latter being formed with a notch or seat for engagement 75 by said latch bar which is released from said notch upon the upward movement of the ring rails as herein shown and specified.

In testimony whereof he affixes his signature.

THOMAS GREAN BULLARD.
